WHEELBARROW

Edmond Balls, Jacksonville, Fla.

Application March 17, 1943, Serial No. 479,515

3 Claims. (CL 298—3)

The present invention relates to new and useful improvements in wheelbarrows, and has for its primary object to provide, in a manner as hereinafter set forth, a device of this character comprising a novel construction and arrangement whereby the load may be expeditiously dumped with a minimum of effort.

Other objects of the invention are to provide a wheelbarrow of the aforementioned character which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is an elevational view, looking at one side of a wheelbarrow constructed in accordance with the present invention.

Figure 2 is an elevational view, looking at the opposite side of the wheelbarrow.

Figure 3 is a view in front elevation of the upper portion of the wheelbarrow.

Figure 4 is a fragmentary view in cross section, taken substantially on the line 4—4 of Figure 1.

Figure 5 is a fragmentary view in cross section, taken substantially on the line 5—5 of Figure 1.

Figure 6 is a fragmentary view in vertical section taken substantially on the line 6—6 of Figure 3.

Referring now to the drawings in detail, it will be seen that the embodiment of the invention which has been illustrated comprises a frame which is designated generally by reference numeral 1. The frame 1 includes a pair of forwardly converging bars 2 having rotatably mounted between their forward end portions a supporting wheel 3. At their rear ends, the bars 2 terminate in handles 4. Supporting legs 5 are provided beneath the bars 2 at an intermediate point.

Mounted for forward and rearward swinging movement in a vertical plane on the frame 1 is a body 6 comprising a forwardly inclined bottom 7. A spring half-hinge 8 supports the body 6 in an elevated position on the frame 1. It will be observed that the supporting hinge 8 is spaced rearwardly from the front end of the body 6 and the bars 2. Projecting forwardly from the

lower front portion of the body 6 over the wheel 3 is a chute 9.

Extending across the upper portion of the front of the body 6 is a bar 10 which is secured between the side walls 11 of said body. Suspended by spring hinges 12 from the bar 10 is a forwardly swinging gate 13 which constitutes the front of the body 6. The spring hinges 12 yieldingly urge the gate 13 forwardly toward open position. Metallic plates 14 and 15 project laterally from the marginal side portions of the gate 13.

Mounted transversely beneath the rear portion of the body 6 and on the bars 2 is a pair of oppositely curved, opposed metallic bars 16 and 17. Depending from the bar 16 is a pair of metallic rods 18 which extend slidably through openings provided therefor in the lower bar 17, said lower bar thus constituting a guide. A coil spring 21 is secured between the bars 16 and 17, intermediate the rods 18, for yieldingly supporting the rear end of the body 6. Integral stops 19 and 20 are provided on the rods 18 above and below the bar 17 and engageable therewith for positively limiting the swinging movement of the body 6 on the hinge 8. Also, the rods 18 have formed therein vertically spaced openings for the reception of nut secured bolts 30 which also constitute stops whereby the swinging movement of the body 6 may be adjusted or regulated as desired.

A latch 22 is pivotally mounted in a housing 23 on the upper front portion of one of the side walls 11 of the body 6 for engagement with the plate 14 for releasably securing the gate 13 in closed position. Slidably mounted on one of the bars 2, adjacent the handle 4, is a manually actuated operator 24 for the latch 22. A cable or the like 25 connects the operator 24 to the latch 22, said cable being trained around pulleys 26 which are provided therefor on the frame 1 and the body 6.

An operator 27 (see Fig. 2) is mounted on the other bar 2 adjacent the respective handle 4. A cable or the like 28 connects the operator 27 to the plate 15 for closing the gate 13, said cable 28 being trained around pulleys 29 which are provided therefor.

It is thought that the operation of the wheelbarrow will be readily apparent from a consideration of the foregoing. Briefly, the body 6 is loaded in an obvious manner and the wheelbarrow is moved to the location at which it is to be dumped. This is accomplished by simply disengaging the latch 22 from the plate 14 through the medium of the operator 24. When this oc-

curs, the gate 13, under the influence of the springs of the hinges 12 and with the assistance of the weight of the load behind said gate, swings forwardly and upwardly to open position, the dirt or other material discharging by gravity beneath the free end of said gate through the chute 9. The limited swinging movement of which the body 6 is capable permits said body to be shaken as may be necessary to loosen any portion of the load that may remain lodged therein. After the wheelbarrow has been emptied, the gate 13 is returned to closed position through the medium of the operator 21 and the cable 28, in which position said gate is again secured by the latch 22.

It is believed that the many advantages of a wheelbarrow constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A wheelbarrow comprising a frame including a pair of forwardly converging bars, a supporting wheel journaled between the forward end portions of said bars, handles on the rear ends of the bars, a body hingedly mounted in an elevated position on the bars for forwardly and rearwardly swinging movement in a vertical plane, a discharge gate hingedly suspended on the front of the body, means for releasably securing the gate in closed position, and means on the body and the frame for limiting the swinging movement of said body in opposite directions.

2. A wheelbarrow comprising a frame includ-

ing a pair of forwardly converging bars, a supporting wheel journaled between the forward end portions of said bars, handles on the rear ends of the bars, a body hingedly mounted in an elevated position on the bars for forwardly and rearwardly swinging movement in a vertical plane, a discharge gate hingedly suspended on the front of the body, means for releasably securing the gate in closed position, and means on the body and the frame for limiting the swinging movement of said body in opposite directions, the last-named means including a pair of oppositely curved, opposed bars mounted transversely beneath the body and on the first-named bars, a pair of rods suspended from the uppermost of the second-named bars and slidably engaged in the lowermost of said second-named bars, stops at spaced points on the rods engageable with said lowermost of the second-named bars for limiting the sliding movement of said rods in opposite directions therethrough, and a coil spring between the second-named bars intermediate the rods for yieldingly supporting the rear end of the body.

25 3. A wheelbarrow of the character described comprising a wheel supported frame, a body hingedly mounted for swinging movement in a vertical plane on said frame, a bar mounted transversely on the frame beneath the body, rods depending from the body and extending slidably through the bar, spaced stops on the rods engageable with the bar for positively limiting the swinging movement of the body in opposite directions, a coil spring connected to the bar and to the body for yieldingly supporting the body, and a discharge gate mounted on the body.

EDMOND BALLS.
